UNITED STATES PATENT OFFICE
2,604,065
DEPTH CONTROL SYSTEM FOR TORPEDOES

William B. Elmer, Lakewood, Ohio, assignor, by
mesne assignments, to the United States of
America as represented by the Secretary of the
Navy

Application August 31, 1945, Serial No. 613,766

2 Claims. (Cl. 114—25)

1. My invention relates to conveyances moving through a fluid medium, and more particularly to depth control devices for controlling the depth of operation of a torpedo.

The Government of the United States has been granted a certain royalty-free license for governmental purposes with respect to the invention disclosed herein.

The advent of the electric torpedo necessitated the provision of electric control means for the rudders and thus also electric control means for controlling the depth of operation of a torpedo. In the prior art devices, apparatus was devised to give proportional control to the elevating rudders, namely a control for operating the elevating rudders by an angle departing from the longitudinal axis of the torpedo proportional to the deflection of a means responsive both to depth and to the angular position of the torpedo axis with reference to the horizontal. Tests with this type of control frequently gave very unsatisfactory results. The torpedo depth records secured from such tests showed that a very erratic course was frequently taken by the torpedo and occasionally the torpedo would broach and at other times it would dive.

One object of my invention is the provision of depth control means that will be simple, reliable, inexpensive and capable of effectively controlling the depth of operation of the torpedo without any tendency of the torpedo to broach or dive.

Another object of my invention is the provision of electromagnetic operating means for the elevating rudders which operate the rudders either to an extreme up rudder position or down rudder position, depending upon either the depth of operation of the torpedo or the angle of motion of the torpedo with reference to the horizon or both.

Another broad object of my invention is the provision of a hard-over depth control for a torpedo in contradistinction to a proportional depth control of a torpedo.

The foregoing objects are merely illustrative since many other objects and advantages will become readily apparent from a study of the following specification if made in conjunction with the accompanying drawing, in which:

Figure 1 is a longitudinal sectional view somewhat schematic of the tail-cone of the torpedo schematically illustrating my invention.

Fig. 2 is a view from the front and partly in longitudinal section of the pendulum structure for effecting the control of the rudders.

Fig. 3 is a side view of the subject matter shown in Fig. 2, and

pendulum structure and depth responsive device, the pendulum structure being pivotally mounted on the longitudinal axis of the torpedo, the pendulum structure including a mass secured to the straps which are pivotally mounted on horizontal pivots, the straps being pivotally mounted on the side plates, the straps being relatively wide and having pivot pins mounted therein which engage the U-shaped structure rigidly secured to the base of the depth responsive device, the U-shaped structure being connected to the base of the depth responsive device, the depth responsive device including a diaphragm for vertically moving the U-shaped member, and to alter the pressure effect of the sea water entering the region above the diaphragm I provide the spring.

50 From this structure it will be apparent that the swing of the weight in its horizontal pivot

will be a function not only of the deviation of the longitudinal axis of the torpedo with reference to the horizon, but also a function of the depth of the torpedo below the sea surface. The pendulum construction just described has been per se used with prior art devices. However, the movement of the pendulum was uti-

Fig. 4 is a plan view looking down on the cover plate for the pendulum structure shown in Figs. 2 and 3.

Proportional control for controlling the depth of a torpedo is apparently an unnecessary refinement, since much quicker response and better control is obtained by throwing the elevator rudders instantly to their extreme limit of travel either to the up-rudder position or to the down-rudder position, depending upon the type of movement required for maintaining a constant depth of operation of the torpedo.

In Fig. 1, 1 designates the tail-cone of the torpedo quite schematically, whereas 2 represents the afterbody of the torpedo usually housing the pendulum structure generally designated by 3 for controlling the depth of operation of the torpedo. In actual practice, there is a bulk-head at the region of the solenoids 4 and 5 to prevent sea water from entering that portion of the torpedo housing my system of control.

The mechanical operating means for the elevating rudders 6 are substantially conventional, except that these mechanical means are coupled to the armatures 7 and 8 coacting with the solenoid coils 4 and 5. The pendulum structure includes a mass 10 secured to the straps 11 and 12 that are pivoted at 13 on horizontal pivots mounted in the side plates 14 and 15 rigidly secured to the casting 16 having an upper plate for hermetical connection to the afterbody of the torpedo. The straps 11 and 12 are relatively wide and have pivot pins 17 and 18 mounted therein which engage the U-shaped structure 19 rigidly connected to the base 20 of the depth responsive portion of my device 21. This depth responsive device includes a diaphragm 22 for vertically moving the U-shaped member 19, and to alter the pressure effect of the sea water entering the region above the diaphragm I provide the spring 23. This spring 23 may be adjusted in its tension by suitable movement of the shaft 25 projecting from the torpedo. Such movement of the shaft 25 also through the worm 26 operates the worm wheel 27 to operate the graduated drum 28 for indicating the selected depth of operation of the torpedo.

From this structure it will be apparent that the swing of the weight 10 in its horizontal pivot will be a function not only of the deviation of the longitudinal axis of the torpedo with reference to the horizon, but also a function of the depth of the torpedo below the sea surface. The pendulum construction just described has been per se used with prior art devices. However, the movement of the pendulum was uti-

lized to actuate rheostats for controlling the energization of the actuating solenoids for the rudders proportional to the deflection of the pendulum. In contradistinction to this method of operation, I provide definite stops 30 and 31 for the rearward movement of the pendulum and 30A and 31A for the forward motion of the pendulum, so that the pendulum is permitted only a relatively small movement from a vertical and in no case is permitted to swing free to thus get into oscillation to produce an effect undesired in the control. Substantially in the vertical plane of the stop 30, I provide switch contacts 32 and 33. One of the contacts, as 33, is resilient so that the stops 30 and 31 will not interfere with their engagement. In operation when the torpedo is either operating at a depth that is too great or has deviated from a horizontal direction of travel, the switch contacts 32 or 33, depending upon the direction of swing of the pendulum, are brought into engagement or disengaged whereupon the solenoids for actuating the rudders are selectively energized. To energize the solenoids, I utilize a battery B and a relay R. A control switch S is closed during the operation of the torpedo. In the event the torpedo is operating in a downward direction and at the proper depth, the circuit for the relay R is closed, whereupon contacts C are closed to establish a circuit from the battery through contact C, solenoid 4, back to the battery. This means that the elevating rudder 6 is moved instantly to its extreme up-rudder position. As soon as the torpedo has ceased its wrong direction of motion and is moved in a horizontal direction or has deviated in an opposite sense from a horizontal direction, the circuit at the contacts 32 and 33 is opened, whereupon the relay R is deenergized and a circuit is established at the back contacts BC. Closure of the back contacts BC energizes the solenoid 5, whereupon the elevating rudders 6 are instantly moved to the extreme down-rudder position, to thus produce an effect on the torpedo in the diving direction.

The relay R is thus caused to flutter back and forth between the energized and the deenergized position and the rudders are moved from the extreme up-rudder position and the extreme down-rudder position repeatedly. The average path of the torpedo, therefore, is found to be in a very accurate horizontal direction.

While I have shown and described but one embodiment of my invention, I am fully aware that others, particularly after having had the benefit of the teachings of my invention, may devise other similar schemes of control for controlling the elevating rudders of a torpedo. I,

therefore, do not wish to be limited to the particular showing herein made nor limited to the particular objects specifically stated, but wish to be limited only by the scope of the claims hereto appended.

5 I claim as my invention:

1. In a system of control for controlling the depth of operation of a torpedo, in combination, elevating rudders for the torpedo, a source of electric energy, solenoid means which, when energized, cause movement of the elevating rudders to their extreme up-rudder position, solenoid means which, when energized, cause movement of the elevating rudders to their extreme down-rudder position, two stops, a pendulum mounted on the torpedo for limited movement to either side of a vertical against said stops, means for connecting the first solenoid means to the source of energy upon movement of the pendulum against one stop, and means for connecting the other solenoid means to the source of energy upon movement of the pendulum away from said stop.

2. In a system of control for controlling the depth of operation of a torpedo, in combination, elevating rudders for the torpedo, a source of electric energy, solenoid means which, when energized, cause movement of the elevating rudders to their extreme up-rudder position, solenoid means which, when energized, cause movement of the elevating rudders to their extreme down-rudder position, two stops, a pendulum mounted on the torpedo for limited movement to either side of a vertical against said stops, means for connecting the first solenoid means to the source of energy upon movement of the pendulum against one stop, means for connecting the other solenoid means to the source of energy upon movement of the pendulum away from said stop, and means responsive to depth for effecting the pendulum movements.
